UNITED STATES PATENT OFFICE.

WILLIAM SCHILDWACHTER, OF WALWORTH, NEBRASKA.

DRILL-ROD EXTRACTOR.

1,163,560.

Specification of Letters Patent.

Patented Dec. 7, 1915.

Application filed March 26, 1914. Serial No. 827,411.

To all whom it may concern:

Be it known that I, WILLIAM SCHILDWACHTER, a citizen of the United States, residing at Walworth, in the county of Custer, 5 State of Nebraska, have invented certain new and useful Improvements in Drill-Rod Extractors; and I do hereby declare the following to be a full, clear, and exact description of the invention, such as will enable 10 others skilled in the art to which it appertains to make and use the same.

This invention relates to drill and pump rod extractors, and is to be used where the drill rod has become broken beneath the 15 surface of the ground, and a broken section has been internally threaded, preferably by the use of the device shown in my application Ser. No. 862,040 filed Sept. 16, 1914.

An object of this invention is to provide 20 for the ready removal of a drill rod which has been broken in the ground.

With these and other objects in view such as will appear as the description proceeds, my invention consists in the combination 25 and arrangement of parts as herein set forth and subsequently claimed.

Referring to the drawing: Figure 1 is a side elevation partly in section, showing my 30 device in place in the drill rod. Fig. 2 is a section on the line 2—2 of Fig. 1.

Referring to the drawing by reference characters wherein similar characters represent similar parts throughout the several views: 1 represents the casing in which is 35 operated a drill rod 2 having a broken section 3.

My device comprises a cylindrical guide member 4 open at each end and having at its lower end removable collars 5 for positioning the guide member 4 concentrically with respect to the broken section 3 of the drill rod. An inverted conical member 6 is secured to the guide member 4 by means of the screws 7 extending through the apertures 8 in the guide member and into the apertures 9 in the collar 10 of the conical member 6. The portion of this member 6 below the collar 10 is screw threaded and has therein diametrically opposite apertures 11 and a centrally located longitudinal aperture 12. In each of the apertures 11 is slidably mounted a gripper member 13 for gripping the sides of the bore in the drill rod when the member 6 has been inserted 55 therein. These members 13 are beveled on

their inner ends, as at 14, and on their outer ends, as at 15, and are provided on their outer ends with knife edges 16. The sliding movement of these members 13 is limited both inwardly and outwardly by 60 the lugs 17 on the member 6 which extend into the slots 18 of the members 13. I provide several of these members 13 at different distances from the ends of the member 6 so that different sized pipes may be gripped 65 and thus extracted. Extending upwardly from the collar 10 is a threaded shank 19 to which is attached the operating member 20 which is actuated by any suitable mechanism. Controlled by this operating member 70 20 is a rod 21 having a beveled end 22 which is pushed downwardly through the longitudinal hole 12 and engages the beveled faces 14 on the members 13 to actuate the same to grip the inside surface of the 75 drill rod.

In operation after the bore in the rod 2 has been threaded my device is lowered in the casing 1 until the guide member 4 encircles the drill rod 2 and is axially positioned on the broken portion 3 thereof by the collars 5. Simultaneously the threaded conical member 6 is screwed into engagement with the threads on the inside of the broken portion 3 of the drill rod, it being 80 understood that the members 13 are at their innermost position during this operation. When the said member 6 is tightly in engagement with the screw threads on the portion 3, the rod 21 is pushed downwardly 85 through the longitudinal hole 12 and thus forces the said members 13 outwardly and into engagement with the threads in the bore of the drill member 2. The knife edges 16 on the said members 13 are thus 90 embedded in the threads and tightly secure the member 6 and the broken portion 3 of the drill rod together so that the drill rod may be lifted from the hole by pulling or unscrewing. It is to be understood that 95 when a small pipe is to be extracted the conical member 6 is inserted into the broken portion of the drill rod far enough so that the lowermost members 13 may be actuated 100 to grip the threads on the bore of the said rod, thus leaving the upper members 13 free to move downwardly to such an extent that they will allow the cylindrical portion of the rod 21 to pass therebetween. After the member 6 has been securely fastened to the 105

110

drill rod 2, the said member and drill rod are extracted from the hole and carry with them of course the casing 4 which is attached to the collar 10 of the member 6. If 5 for any reason I desire to withdraw the member 6 from the drill rod I may do so by withdrawing the rod 21 from the hole in the member 6 which allows the members 13 to be disengaged from the screw threads on the 10 inside of the drill rod and the said member 6 may then be unscrewed and withdrawn. When it is necessary to withdraw a drill rod which is inclosed by a large casing I provide the lower end of the guide 4 with one 15 or more collars detachably held on the guide by screws 22', it being understood that each collar extends out farther than the one on which it is mounted so that the member 6 may be centered in any size drill rod casing 20 by the use of the appropriate number of collars.

It may be seen that I have provided a device wherein a portion thereof may be engaged with a broken portion of a drill 25 while the latter is in place beneath the ground, and I have further provided means for clamping my device to the said broken portion of the drill rod.

I do not wish to be limited to the particular construction of my device shown,

for it is obvious that numerous changes may be made without departing from the spirit of my invention and within the scope of the claims.

What is claimed is:—

1. In a device of the class described, an inverted threaded conical shank having a longitudinal hole therethrough and transverse holes intersecting said longitudinal hole and extending through the face of the 35 conical member, gripping members mounted in said transverse holes, said gripping members being beveled on their inner ends and having knife edges formed on their outer ends, means in said longitudinal aperture 40 for actuating the said gripping members, and means to limit their movement.

2. A drill rod extractor comprising a guide, removable positioning means on said guide, a threaded downwardly extending 45 conical shank mounted within said guide, gripping members slidably mounted on said shank, means for operating said gripping members, and means to actuate the shank.

In testimony whereof, I affix my signature, in the presence of two witnesses.

WILLIAM SCHILDWACHTER.
